ABSTRACT

A method and an apparatus for closing the toe of a stocking, wherein a closing thread is laid or knitted into the toe end of a tubular mesh, which closing thread passes at least once around the entire periphery of the mesh. The mesh is cast off the needles of a circular knitting machine and the closing thread is then pulled or partially drawn out of the mesh, causing the mesh to be constricted so as to close the toe thereof. The closing thread is then secured, as by being knotted, to prevent same from being pulled back into the mesh.

METHOD AND APPARATUS FOR CLOSING THE TOE OF STOCKINGS OR STOCKING TIGHTS

The invention relates to a method and apparatus for closing the toe of stockings or stocking tights which are produced in the form of a tubular or hose-shaped mesh on the needles of a circular knitting machine.

In practice there are two previously known methods for closing the toe part of stockings. In one method the loops are first decreased, then increased on the circular knitting machine to produce the toe part, thereby providing a stocking which is closed at the toe, but which has a slit passing round half of the periphery of the stocking at the point where decreasing of the loops commences. The stocking is then transferred to a separate machine and the slit is linked. This method provides stockings with faultless closed toe parts of pleasing appearance, but, because of the additional operation required to close them, it is complicated and costly. It is therefore only used for high-quality ladies' stockings and, to a greater extent, for men's socks. The other known method consists of the stocking being knitted in the form of an open tube as far as the toe part. It is then cut off obliquely, the cut edge is turned down and the opening sewn up. In this connection it is necessary to turn the stocking twice, since it is knitted to the right, sewn to the left and then boarded again to the right. Turning the stocking twice and sewing entail a considerable amount of work. Moreover, there is the danger that the stockings may be damaged during turning. In spite of this disadvantage this method is generally used nowadays for most ladies' stockings and, to a lesser extent, for men's socks.

The prior art also includes a method (British Pat. specification No. 1,037,200) whereby the toe is closed by twisting. For this purpose knitting of the stocking commences at the toe and a ring-shaped mesh, loop-shaped in longitudinal section, is first produced by feeding at least the first course on to the sinkers of the welt dial. Cams 133 and 136 are inserted radially upon passage thereby of section of needles with short butts (not shown). Then the welt dial is twisted relative to the needle cylinder. In this movement one edge of the initially loop-shaped mesh is shifted through a greater angle than the opposite edge. The mesh is thereby twisted in the centre to such an extent that a practically closed toe is produced. Finally the course of loops initially transferred on to the transfer sinkers is again fed to the needles and the knitting operation is completed. In this known method it is impossible to prevent a relatively large accumulation of material on and particularly in the middle of the toe part. This accumulation of material is due to the double-layered mesh in the vicinity of the toe and the twisting together of the mesh in the centre of the toe. The greater the accumulation of material, the more secure is the closure of the toe. Moreover, the method may only be put into practice on a special machine suitable for this purpose, in which the welt dial can be twisted relative to the needle cylinder.

The problem underlying the invention is to provide a method for closing the toe of socks or stockings, which can be carried out actually on the circular knitting machine and which ensures reliable closure of the toe without excessive accumulation of material in the toe area. This problem is solved in accordance with the invention if an additional toe-closing thread is fed into

the tube-shaped mesh in the vicinity of its edge on the side of the toe so that it passes at least once around the periphery of the mesh and is then pulled out relative to the mesh which shrinks until an essentially closed toe is formed, and so that the toe-closing thread is finally secured against withdrawal.

The invention is based on the notion that it is possible to sew up and therefore close a tubular mesh if a thread is pulled out of a course of loops. When stockings are worn, this effect is known in the negative form of so-called "snags," but it is positively exploited by the invention to close the toe in a simple manner. For this purpose a separate thread is usually laid in for closing the toe, since the thread which forms the actual mesh is normally too thin to pull out. The toe-closing thread passes at least once around the entire periphery of the stocking. After the mesh is cast off the needles, the toe-closing thread is deliberately pulled out, whereupon the tubular or hose-shaped mesh is strongly constricted at the point where the toe-closing thread is located and a closed toe is formed. The toe remains closed because the closing thread is then secured against being pulled back. In the main these steps can be carried out on a known circular knitting machine on which only a few extra units need to be fitted for pulling out the closing thread and preventing it from being pulled back. There is not a great accumulation of material in the vicinity of the toe formed in accordance with the invention, since the toe is not twisted.

The closing thread is advantageously laid into and out of the mesh so that, after being laid out, it forms two ends projecting from the mesh, said closing thread being gripped and drawn out at the projecting ends. The toe is uniformly constricted and completely closed by pulling the closing thread out at both projecting ends.

It is advantageous if the toe-closing thread is laid in and out at essentially the same point on the periphery of the mesh so that the two ends lie in juxtaposition. The ends lying thus can be easily gripped and drawn out with one pull.

The drawn-out closing thread can be particularly advantageously secured against withdrawal by knotting the drawn-out ends. The knotting may be simple effected and the closing thread is effectively secured against withdrawal without a substantial accumulation of material.

It is expediently provided that a double-layered zone for closing the toe be formed in the mesh and the closing thread be laid approximately in the centre of said closing zone. In this case the toe is mainly knitted in one layer and a double layer only exists in the closing zone, thereby producing a firm and neatly finished toe closure.

In order to prevent the formation of ladders originating in the closing rows, the latter can be knitted in a ladder-proof pattern. It is simpler if a thread which shrinks substantially when subjected to heat treatment is knitted in the closing rows of the mesh on the toe side. During figuring or shaping by heat this thread shrinks and contracts the loops of the closing rows to such an extent that no ladder can occur therein. No additional operation is required to prevent the formation of ladders since heat treatment of the stocking is necessary in any case.

The withdrawal of the thread for toe closure is facilitated if it is laid in only some of the needles.

Instead of the closing thread being gripped and drawn out by its ends, it is possible to proceed in such a manner that the closing thread is laid in the mesh so that it is held therein by its ends and forms at least one floating section, and that, when it is drawn out, the closing thread is gripped on the floating section. The floating section can be gripped relatively easily by an extracting tool which penetrates into the tube-shaped stocking mesh.

The beginning and end sections of the toe-closing thread are advantageously knitted into some of the loops in the mesh and, apart from at least one completely floating section, have such sections which are laid into only a part of the loops in the mesh. In this method the beginning and end of the closing thread are firmly held in the remaining mesh. The closing thread has at least one intermediate floating section which can be easily gripped by a pulling or supporting tool. In addition the closing thread between the beginning and end sections is only laid into part of the loops. The thread may thereby be drawn out with the minimum of effort to close the toe, but it nevertheless passes around the entire periphery of the mesh so that it is evenly constricted at a plurality of closely adjacent points on the periphery.

In accordance with an important elaboration of the invention it is provided that the closing thread should have two or more completely floating sections covered by sections in which it is laid into every loop or part thereof. In this way there are provided two or more floating sections on which it is possible to pull. This diminishes the risk of breaking the closing thread when the toe part is being constricted. In spite of this all parts of the toe are evenly drawn together, since the closing thread is provided with at least partially laid-in sections distributed over the entire periphery of the stocking.

Loops narrower than in the remaining mesh are expediently formed in that part of the mesh in which the beginning and end sections of the closing thread are knitted. The ends of the toe-closing thread are gripped particularly securely in the remaining mesh, and the closing thread cannot be fully removed when the toe part is constricted.

Moreover, it is advantageous if wider or larger loops are formed in that part of the mesh, in which sections of the closing thread lying between the beginning and end sections are laid rather than in the remaining mesh. Therefore, when the closing thread is pulled out, little resistance occurs because the closing thread can slip with greater ease through the wider loops.

The constriction of the toe by means of the closing thread can be effected in a particularly simple manner because, during constriction of the toe, the mesh is drawn into an opening too narrow for it to pass through by pulling the floating sections(s) of the closing thread and is thereby retained in opposition to the pulling force acting on the closing thread.

The toe-closing thread can be secured in various ways against withdrawal after the toe is constricted. It is advantageous to sew up, knot or glue the closing thread or to weld it by the application of heat or ultrasonics. A combination of these steps can also be used. Welding would be the most advantageous method, if a thread made of thermoplastic material is used. The constricted edge of the mesh at the toe end can be sewn up, knotted, glued or welded at the same time as the closing thread. A combination of these measures is also

possible in this case. Welding is also offered as the optimum solution in this case, when the stocking is made of a thermoplastic yarn.

In order that the floating section of the closing thread may be gripped with particular ease, it is possible to proceed so that, after being laid in the needles, the toe-closing thread is laid out and then laid in again at least once during at least one complete cycle of the circular knitting machine so that the floating section forms a loop, the length of which is at least equal to the radius of the tubular mesh. In this way each floating section forms a loop of such length that it stretches as far as the centre of the mesh. Such loops may be easily gripped in the centre of the needle cylinder by an extracting tool, such as a hook. The removal of the closing thread is thereby considerably simplified.

It is particularly advantageous if each loop is laid in the centre of the tubular mesh while the knitting operation is performed around a retaining or extracting member. In this case the loops are all laid around the extracting tool during knitting, so that the removal of the toe-closing thread is directly associated with the knitting operation.

The closing thread can be secured particularly simply and effectively against withdrawal, if the ends or the loop of the closing thread are twisted after or during its removal and glued together to prevent withdrawal.

The ends or sections of the thread forming the loop are closely joined by twisting. This connection is maintained by an adhesive so that the closing thread cannot be drawn back into the mesh.

The closing thread is secured against withdrawal to a particularly high degree if, according to another advantageous development of the invention, a ball is formed in the closing thread by loosening the twisted ends or loop thereof and the ball is glued together. It is generally known that, during the twisting of two or more threads, a longitudinal tension is produced in the twisted thread formation so that the latter contracts axially during loosening and forms a ball of thread. If this ball is then glued together, so many adhesive joints and such a great amount of reinforcing material are produced at the joint that the closing thread can no longer be safely drawn into the mesh.

The ends of the closing thread or the sections forming the loop are particularly tightly glued together, if adhesive is applied to the ends or loop of the closing thread before twisting.

In order that the various modifications of the method according to the invention may be put into practice on the conventional circular knitting machines comprising a rotatable needle cylinder, in which needles are mounted for longitudinal displacement, a sinker ring, which concentrically surrounds the upper edge of said needle cylinder and in which are disposed radially displaceable cast-off sinkers, and at least one thread guide for feeding the knitting thread, it is necessary to modify and supplement these circular knitting machines in various ways.

A circular knitting machine suitable for the method first described is characterized in accordance with the invention by at least a second thread guide for feeding the closing thread, a cover disk rigidly mounted above the needle cylinder and having an opening which is open towards the edge of the disk above a slot and into which the stocking toe part can be drawn and retained therein, a controlled thread-clamping device mounted

on the cover disk for temporarily gripping the closing thread, a controlled pulling means disposed between the thread-clamping device and the opening for extracting the closing thread, a controlled cutting device located on the cover disk for casting off the toe-closing thread, and an arrangement mounted on the cover disk next to the opening for securing the closing thread against withdrawal.

In this embodiment of the circular knitting machine in accordance with the invention, the projecting ends of the closing thread are held in the thread-clamping device while the pulling means engages on the ends between the clamping point and the mesh and draws out the closing thread. In this connection the toe is drawn into the opening in the cover disk and retained therein. Joint removal of the ends is possible because they pass into the opening through the slot in the cover disk when the needle cylinder is rotated. Since the device for securing the closing thread against withdrawal is arranged in direct proximity to the opening, only a very short piece of thread remains projecting from the closed toe after the closing thread is cast off.

The thread-clamping device is advantageously associated with a suction device for drawing away the cast off ends of the closing thread and for temporarily holding a closing thread end. The suction device serves to carry away the cast-off ends and, at the same time, to flexibly retain a thread end.

The device for securing the closing thread against withdrawal consists advantageously of a knotting means of a design known per se mounted above the opening in the cover disk, and a vertically movable thread control plate which co-operates with said knotting means. The formation of a knot on the protruding ends of the closing threads provides an effective securing against withdrawal with a small amount of thread accumulating in the toe area.

It is even more advantageous if the device for preventing withdrawal of the closing thread comprises a knotting hook rotatably mounted above the opening in the cover disk, the lower end being mounted so that it swivels laterally and comprising two superposed, laterally extending prongs, of which the lower one is hook-shaped, and the side of the knotting hook turned away from the prongs is bevelled or rounded at the bottom, a vertically movable thread control plate co-operating with said knotting hook. With such a hook which, in contrast to a knotting device of normal construction, has no relatively movable openings for knotting, the knot can be formed even closer to the toe of the stocking, thereby further reducing the amount of closing thread still remaining on the toe.

The thread control plate can have a lower cutting edge which co-operates with a cutting edge rigidly mounted opposite on the cover disk. In this case the thread control plate has two functions, namely, to co-operate with the knotting hook or the like to form the knot and to cast off the thread after the knot is formed. A thread control plate thus designed can be provided when either a knotting device of normal construction without any cutters or the described knotting hook is used.

German Pats. No. 1,169,072 and 1,201,939 disclose castoff sinkers of a special design which are used for retaining the first course of loops when a double welt is formed as well as for normal knitting in co-operation with the needles. It is advantageously provided that

those sinkers, which have an additional radial groove for the temporary retention of the first courses, be used in the circular knitting machine. In this case the welt dial necessary for forming the double welt can be omitted and replaced by the stationary cover disk mentioned.

In order to carry out the method wherein the extracted toe-closing thread is twisted and glued together, it is particularly advantageous to use a circular knitting machine which is characterized by a rotatable and longitudinally movable hook, by which the closing thread can be extracted and twisted, and by an adhesive applicator associated with said hook.

In this circular knitting machine of the invention a tool, namely the hook, is used both to pull the toe-closing thread out of the mesh and to twist said thread. The closing thread is therefore extracted and secured against withdrawal by simple constructional means.

The hook expediently forms the extention to a shaft of a motor which is slidably or pivotably mounted above the needle cylinder in the longitudinal direction of the shaft. In this example the hook is rotatably driven directly by the motor without any intermediate members, the longitudinal movement required for extracting the thread being ensured by the movement of the motor along with the hook.

In this way twisting can be effected while the toe-closing thread is being extracted so that little time is required for closing the toe.

It is expediently provided that the adhesive applicator should have a spray nozzle which is arranged next to the path of movement of the hook and filled with adhesive by a supply container in synchronisation with the movement of the hook. The adhesive is sprayed through the nozzle on to the twisting closing thread so that the thread is thoroughly impregnated with adhesive.

The hook is advantageously associated with a pair of cutters for cutting off the ends or loop of the closing thread after it is glued. The thread ends may thereby be cut off immediately after the thread is extracted and glued together, whereupon toe closure is completed.

The invention will be described below with the aid of exemplary embodiments together with the drawings.

FIG. 1 is a schematic representation of the toe-closing thread passing once around the periphery of the mesh in the toe area of a stocking before the ends of the closing thread are removed,

FIG. 2 shows an illustration corresponding to FIG. 1 with the closing thread passing twice around the periphery of the mesh,

FIG. 3 shows another possible course of the closing thread having two projecting ends and a floating section,

FIG. 4 is a schematic representation of the toe closure with the course of the closing thread as shown in FIG. 1 after the removal of the closing thread has commenced,

FIG. 5 shows a view corresponding to FIG. 4 shortly before the removal of the closing thread is completed,

FIG. 6 is a schematic representation of the stocking toe closed according to the method of the invention,

FIG. 7 shows a schematic vertical section through a circular knitting machine for carrying out toe closure as shown in FIGS. 1 to 6,

FIG. 8 shows a side view of the arrangement for controlling the units of the circular knitting machine shown in FIG. 7 which are involved in the toe-closing operation.

FIG. 9 shows a plan view of the illustration shown in FIG. 8.

FIGS. 10 a-d show schematic plan views of the units co-operating in the toe closure in four different working positions,

FIG. 11 shows a side view of the hook used for extracting the toe-closing thread,

FIG. 12 a-c show side views of the thread-clamping device in three different positions, said device being used for retaining the ends of the closing thread during extraction,

FIGS. 13 a-g shows schematic views of the knotting members of normal construction in different working positions, which knotting members can be used for knotting the ends of the closing thread,

FIG. 14 shows a vertical section through a circular knitting machine with which another modification of the method according to the invention can be put into practice,

FIG. 15 shows a schematic plan view of the edge of the mesh on which the toe is formed in accordance with an embodiment of the method of the invention,

FIG. 16 is a schematic representation of the needle control for forming a toe with the machine shown in FIG. 14,

FIGS. 17 and 18 show two schematic views of needle insertions as they can be provided for carrying out the method of the invention on the machine as shown in FIG. 14,

FIGS. 19 and 20 show partial views of two sections of mesh in the vicinity of the edge which forms the toe, said mesh corresponding to the needle insertions shown in FIGS. 17 and 18,

FIGS. 21 to 23 show three perspective views of successive operations during the closing of the toe,

FIG. 24 shows a view, corresponding to FIG. 15, of a modification of the method according to the invention,

FIG. 25 shows a schematic view of the area of mesh forming the toe in another modification of the method according to the invention,

FIG. 26 shows a vertical section through a circular knitting machine of the invention with which another modification of the method according to the invention may be put into practice,

FIG. 27 shows a section of the upper part of the machine, corresponding to FIG. 26 and turned through 180° with various parts, not essential to the invention, having been omitted for the purposes of clarification,

FIG. 28 shows a cross section through the machine along the line 111 — 111 in FIG. 27,

FIG. 29 shows a side view and partial section of the drive for the cutters of the machine shown in FIGS. 26 and 27,

FIG. 30 shows a plan view of the illustration shown in FIG. 29, and

FIGS. 31 a-c schematically represent the toe-closing operation in different stages.

The schematic view in FIG. 1 shows a toe-closing thread S passing around the periphery of an unshown tubular stocking mesh. The thread S is laid in at the position E, a thread end S_e being retained outside the

mesh. After the needle cylinder has completed one rotation, the closing thread S is laid out again at A and a second thread end S_a is formed. The schematic view in FIG. 4 shows that the thread ends S_e and S_a are gripped at K some distance from the mesh G and, as shown at Z, pulled out by an extracting means while the mesh G is retained. The open end of the tubular mesh is thereby constricted, as shown by comparing FIGS. 4 and 5. In the latter figure the extracting of the ends of the closing thread is further advanced. In FIG. 6 the toe is completely closed at S_p, and withdrawal of the closing thread S is prevented, for example, by a knot.

FIG. 2 shows an alternative method of laying in the closing thread S₁. This thread is laid in at E₁, again while forming an end S_{1e}, then passes twice around the periphery of the mesh in order to be laid out at A¹, thereby forming another end S_{1a}. Removal of the thread is effected exactly as in FIGS. 4 and 5 by means of an extracting means Z, while the ends S_{1e}, S_{1a} are clamped and the mesh G retained. Another possible method of laying in a closing thread S¹¹ can be seen in FIG. 3. In this case the closing thread is laid in at E¹¹, thereby forming an end S^{11e}, then passes slightly more than once around the periphery of the mesh, is laid out at A¹¹₁ until a floating section F¹¹ is formed, in order to be laid in again E¹¹₂ and passes slightly more than once around the periphery of the mesh until the thread is laid out at A¹¹₂ for the second time while an end S^{11a} is formed. The closing thread S¹¹ is then removed as in FIGS. 4 and 5, only the ends S^{11e}, S^{11a} or the floating section F¹¹ being drawn out.

A toe-closing thread S corresponding to FIG. 1 can be laid in and drawn out, while the mesh G shown in FIGS. 4 to 6 is retained, on a circular knitting machine as shown in FIGS. 7 to 9. The circular knitting machine comprises a housing 1, the lower unshown part of which includes a drive schematically represented at 2. A needle cylinder 3 is rotatably mounted in the housing 1 and its outer side is provided with longitudinally extending guide grooves 4. Latch needles 5 are mounted so as to be longitudinally displaceable in the guide grooves 4. The rotation of the needle cylinder 3 is effected by the drive 2 via a main shaft 6, a gear wheel 7 supported thereon and a spur gear 8 surrounding and rigidly connected to the needle cylinder. During the rotation of the needle cylinder the needles 5 are controlled in their longitudinal movement by cylinder cams 11 and 12 which are supported in a bush 13 rigidly connected to the housing 1. A stationary funnel 14 is located inside the needle cylinder 3 for removing knitted articles.

The upper part of the needle cylinder 3 is enclosed by a sinker ring 15 non-rotatably connected thereto. The sinker ring has cast-off sinkers 17 contained in radial grooves 16. The radial movement of the cast-off sinkers 17 is controlled by a fixed sinker cam ring 18 which is rigidly connected at 19 to a yoke or shoulder 20 which is in turn rigidly supported by a frame 21 on the housing 1.

The illustrated machine has no welt dial, but can nevertheless produce stockings with a double welt. Such machines are described, for example, in the German Pats. No. 1,169,072 and 1,201,939. For this purpose the sinkers 17 are specially designed with an additional radial groove or recess so that they can be used for retaining the first course of loops while the double welt

is formed, as well as for normal knitting in co-operation with the needles 5.

In place of the welt dial there is a fixed cover disk 50 mounted on the yoke 20 co-axially with and in the vicinity of the upper edge of the needle cylinder. The centre of this cover disk has an opening 22 which tapers conically upwards. A couple of thread guides 27a are pivotably mounted on the yoke 20 and feed two kinds of thread to the needles 5 from unshown bobbins which are rotatably mounted on the machine frame. These types of thread are used to knit the stocking. Another thread guide 27b is pivotably mounted in an unshown manner on the yoke 20 on the side lying opposite thread guides 27a in relation to the cover disk 50. This thread guide feeds the needles with the closing thread S which comes off a likewise unshown bobbin, when it is located in the lowered working position shown. Also a suction tube 51 is mounted in the vicinity of the thread guide 27b on the concealed part of the yoke 20 and air is drawn into said suction tube by means of an unshown pump.

Working inwards from the outside of the cover disk 50 on the side facing the thread guide 27b, a thread-clamping device 52, an extracting hook 53, an arrangement 54 for preventing the withdrawal of the toe-closing thread and a thread control plate 55 co-operating with the latter are mounted in juxtaposition. These components are mounted on arms of the yoke 20 shown in FIG. 7, at 20a. In the embodiment shown in FIG. 7, the arrangement 54 for preventing withdrawal of the closing thread S is in the form of a knotting device of normal construction comprising a pair of jaws 57, a guide ring 58 and a drive shaft 59. The latter is driven by a bevel gear wheel 60 via a bevel pinion 61. The drive and control arrangements for the thread-clamping device 52, the extracting hook 53, the device 54 for preventing the withdrawal of the closing thread S and the thread control plate 55 can be seen better in FIGS. 8 and 9 from which the remaining parts have been omitted for the sake of clarity.

The thread-clamping device 52 has a shoe 52a which is pivotably mounted about an axis 62 in the arm 20a of the yoke. A deflecting pin 63 is resiliently mounted on the side of the clamping shoe 52a. A tension spring 64 endeavours to move the shoe 52a downwards into the clamping position.

The extracting hook 53, which is shown in the lowered position in FIG. 7, but in the raised position in FIG. 8 has a hooked head 53a and can be pivoted about an axis 65 disposed in the arm 20a of the yoke. A spring 66 endeavours to draw it into the raised position. It can be seen in FIG. 11 that, when the extracting hook 53 is in the lowered position, its head 53a engages in a recess 67 in the cover disk 50.

The arrangements involved in the closure of the toe are controlled by a cam control drum, generally designated by reference numeral 69, FIGS. 8 and 9 wherein several cam plates are disposed on a shaft 70 mounted in the arm 20a of the yoke. The first cam plate 69a controls a two-armed lever 71, which can be pivoted about an axis 72, one of its arms bearing against the cam plate and its other arm pivoting the shoe 52a of the thread-clamping device 52 in opposition to the force of the spring 64. The second cam plate 69b controls another two-armed lever 73 which is pivotably mounted about the same axis 72, one arm bearing against the associated cam plate and the other arm engaging from

below on the thread control plate 55, pivotable about the axis 62, and pivoting it about said axis 62 in opposition to the force of a spring 74. A third cam plate 69c acts upon a cam follower 75 which is rigidly connected to the hook 53. This cam plate pivots the hook 53 about the axis 65 in opposition to the force of the spring 66. A final cam plate 69d actuates a two-armed lever 76 which can pivot about an axis 77 of the arm 20a. This lever is subjected to the force of a spring 78 and is connected to the bevel gear wheel 60 by a pin and slot coupling 79.

The cam control drum 69 is driven by a central control device 29 which is only schematically represented. It acts via a lever mechanism upon a driving ratchet 80 which controls the drum 69 step by step via a ratchet gear wheel 81 connected thereto. A switch cam 83 can be pivoted by a lever 82, which can also be actuated by the control device 29, which switch cam is rotatable and can disengage the ratchet 80 and ratchet gear wheel 81 by lifting the former out of the latter, when the components involved in closing the toe are to be rendered inoperative. The central control device 29 can be driven by the main drive shaft 6 and, in addition, controls the cylinder cams 11 and 12, the thread guides 27a and 27b as well as the air source for the suction tube 51. The controlling connections, which can be produced by mechanisms or electric or hydraulic connections, are indicated in the drawing by broken lines.

During the operation the needles 5 cooperate with the sinkers 17 to form a mesh G from a thread which is fed in by one of the thread guides 27a. This is a known operation and does not require a detailed explanation.

To produce a stocking with a closed toe by means of the circular knitting machine described, it is operated as follows:

If the closing zone of the toe of the stocking is obtained during knitting, half of the needles 5 are entirely withdrawn from the knitting area in a 1:1 selection. The other half continue operating normally. The inoperative needles hold their loops until they are reintroduced towards the end of the knitting operation. With this 1:1 selection every second needle 5 forms a knitted loop over the entire cylindrical periphery. Thus, about 10 to 12 courses of loops are knitted. Then knitting needles 5 in a 1:3 to 1:8 selection are guided upwards in front of the thread guide so that they remove the toe-closing thread from the lowered thread guide 27b, guide the closing thread downwards and insert it into part of the loops in the mesh G. The selection of the needles is determined by the fineness or size of the loops. The coarser or larger the loops, the finer is the selection. A selection of 1:5 or 1:6 is made when 400 needles are in use. During at least one complete cycle of the needle cylinder 3, the closing thread S is laid in this manner into every third to eighth needle.

The operations occurring during and after the laying in of the closing thread S are described as follows with the aid of FIGS. 10a-d which show a plan view of the cover disk 50, clarified by the omission of other parts. First, it can be seen that the opening 22 is circular and open towards the edge of the cover disk by means of a slot 84 which extends in the form of a steep logarithmic spiral.

Before the operation of laying in the closing thread S commences, the thread-clamping device 52 is lo-

cated in the position shown in FIG. 12a in which it is fully open. The lower end of the deflecting pin 63 is located at a distance from the surface of the cover disk 50. The free thread end S_e , left after the previous closing thread was laid in, leads from the raised thread guide 27b past the front of the deflecting pin 63 and under the raised shoe 52a, then passes, from behind, over said shoe 52a into the suction tube 51, where it is flexibly held by the suction of air. The ratchet 80 is then engaged and drives the cam control drum 69 via the ratchet gear wheel 81. The above-described initial position is schematically illustrated in FIG. 10d.

At the beginning of the operation, the closing thread guide 27b is lowered into the working position, and the thread-clamping device 52 is moved into the half-open position shown in FIG. 12b. In this position the shoe 52a is still removed from the surface of the cover disk 50; however, the lower end of the deflecting pin 63 is supported in a recess 85 in the cover disk. The closing thread S that is the portion thereof which extends between the guide 27b and the shoe 52a is gripped by the needles 5, which are guided up into the catch position and laid-in or interlaced into several loops of the mesh G. The rotation of the needle cylinder 3 (counterclockwise in FIG. 10) when the deflecting pin 63 is lowered then causes the thread end S_e to be drawn around the pin 63, under the shoe 52a, into the slot 84, over the hook head 53a which is positioned as shown in FIG. 11 and finally into the opening 22 of the cover disk 50. From there a portion of the thread end S_e extends below the cover disk 50 (as illustrated by the dotted line in FIG. 10a) towards the foremost needle which has gripped the closing thread S. This position is indicated in FIG. 10a. In this connection the free end S_e of the closing thread has been drawn back slightly out of the suction tube 51 by opposing the force of suction.

As soon as the needle cylinder 3 has completed at least one revolution, the thread guide 27b is raised again so that the toe-closing thread S is laid out. A rear thread end S_a (which is not yet severed from the supply thread S) of the closing thread S is removed from the raised thread guide 27b by the continuing rotation of the needle cylinder. This thread end is also drawn into the slot 84 by the progressive rotation of the needle cylinder 3. This position is indicated in FIG. 10b. With continuing rotation of the needle cylinder this end S_a also passes into the central recess 22 and is located in front of the deflecting pin 63, under the still half-open thread-clamping device 52 and above the head 53a of the hook 53. This latter position is shown in FIG. 10c. The thread-clamping device 52 is then lowered into the closing position which can be seen in FIG. 12c. When in this position, the shoe 52a presses down on to the cover disk 50. This requires a relative movement between the deflecting pin 63 and the clamping shoe 52a, which is made possible by the flexible deflecting pin 63 and the bent support on the side of the shoe 52a. By lowering the shoe 52a the two thread ends S_e and S_a are rigidly clamped on the cover disk 50. Further rotation of the needle cylinder only causes the thread ends S_e , S_a to be twisted.

The needles then knit about 10 to 12 courses in a 1:1 selection, thereby producing a mesh in the centre of which the closing thread S is laid. The length of this two-layered mesh can naturally be more or less than 10 to 12 courses. However, it is important that the size of

the loop be altered equally on either side of the closing thread S.

After the mesh is completed, all the needles are returned to the operative position. Then a few closing rows are knitted. Alone or combined with the previously used thread, these rows consist of a thread which shrinks considerably with thermal treatment and is fed in through one of the two thread guides 27a. When the stocking is figured or shaped by heat treatment this 10 thread shrinks considerably so that the marginal loops are constricted and no ladders can originate at the end of the stocking even in the case of very short closing rows.

After the closing rows are completed, the stocking is 15 pressed off the needles 5.

While the second half of the two-layered mesh is being knitted, the extracting hook 53 is gradually raised. The closing thread S is drawn taut whereupon the mesh is stretched and straightened. After the stocking 20 is pressed off the needles 5, the hook 53 is moved into its uppermost position while thread-clamping device 52 remains closed. It thereby draws the toe S_p of the stocking up into the conical opening 22 where it is retained. The toe is therefore constricted in the manner 25 described initially with the aid of FIGS. 4 to 6, the part Z being formed in the exemplary embodiment by the hook head 53a and the part K by the thread-clamping device 52. When the toe S_p is closed, the ends S_e , S_a of the closing thread S are secured against withdrawal. 30 This can be effected by welding (as illustrated in FIG. 14), gluing (as illustrated in FIGS. 26-31), sewing, but preferably by knotting. A conventional knotting arrangement 54 is used for this purpose. Knotting devices similar to the device 54 illustrated in the attached drawings are known, and a similar such device is disclosed in U.S. Pat. No. 312,790, issued to J. F. Appleby. U. S. Pats. No. 319,167, 1,726,396 and 2,670,230 also disclose knotting devices which possess structural and operational features similar to the knotting device of this application.

The mode of operating the prior known knotting device 54 shown in FIG. 7 can be seen in FIGS. 13 a-g:

First the knotting jaws 57 and 57' are rotated by 45 means of the shaft 59 which is rotatably supported by the eccentric control ring 56, which ring 56 as illustrated in FIG. 8 is supported upon the shaft 58. The control ring 56 is normally maintained in engagement with a fixed stop, such as the stop pin 56a illustrated in FIG. 8, as by means of a spring (not shown). Shaft 58 in turn rotatably supports thereon a bevel gear 60 which is in meshing engagement with a further bevel gear 61 which is nonrotatably secured to the shaft 59. The bevel gear 60 is in turn driven by a lever 76 and a pin-and-slot coupling 79 as shown in FIGS. 8 and 9. The thread guide plate 55 is lowered and thereby holds the thread ends S_e , S_a , which are drawn upwards by the extracting hook 53 and held firmly on the other side of the hook in the thread-clamping device 52, in such a 50 position that they slide over the jaws 57 and 57' which are located at the same level (FIG. 13a). When the jaws are rotated further, they are moved or cammed apart by the eccentricity of the surrounding control ring 56, (FIG. 13b) contacting and moving the pivotal jaw 57', but the thread guide plate 55, lowered even further, holds the thread ends S_e , S_a below the opened jaws. On 55 further rotation a loop is formed between the stocking

toe S_p and the knotting device 54 (FIG. 13c). Then the thread guide plate 55 is slightly raised again so that, when the knotting device rotates further, the thread ends S_e , S_a are produced between the open knotting jaws 57 and 57'. On further rotation the thread ends are gripped firmly between the jaws which can be seen in FIG. 13e showing the knotting device turned through 90°. Then the knotting device 54 is tilted sideways. In order to effect this tilting movement, the rotational movement of the bevel gear 61 due to the driving thereof by the gear 60 is checked after the jaws have been rotated twice, which checking occurs for example due to a stop pin 60a (FIG. 8) which is provided on the bevel gear 60 and moves into engagement with the teeth of the gear 61 to prevent further meshing engagement therebetween. The stop pin 60a thus causes the gears 60 and 61 to lock up so that further driving of the gear 60 by the lever 76 causes the gears 60 and 61 and the control ring 58 and the shaft 59 supported thereby to swing as a unit about the axis of the shaft 58 away from the stop pin 56a, thereby tilting the jaws so that the knot may slip off the jaws. After the knot has been removed from the jaws, the gear 60 and the associated structure is then returned to its original position.

The tightly clamped thread ends are drawn through the formed loop and then the knot is tightened by a tilting movement, the first stage of which is shown in FIG. 13f and the final stage in FIG. 13g. Then the thread ends S_e , S_a , are cut by any suitable device, either manually or automatically thereby terminating the knotting operation and leaving the closing thread secured to the tubular mesh.

The completely severed thread end S_e is drawn into the suction tube 51 as soon as the thread-clamping device 52 opens again. The other thread end S_a , still hanging in the thread guide 27b and connected to the supply thread S, is drawn over the shoe 52a and into the suction tube 51 and held therein until a further toe-closing thread S is laid in again.

For cutting the closing thread, a cutting device as illustrated in FIGS. 13a and 13b may be provided. For example, the thread control plate 55 may be provided with a cutting edge 55a on the lower end thereof positioned for cooperation with another cutting edge 87 rigidly mounted on the cover disk 50.

After the knot is completed and released, the stocking leaves the circular knitting machine with the toe S_p closed.

In the method described, knitting of the stocking can commence on both the double welt and the toe. In both cases a closed toe can be produced.

In order to bring the toe-closing zone further under the toes, the upper portion of the toe can be oscillated in known fashion or provided with longer loops. Additional courses of loops can be knitted. For the same purpose, the lower portion of the toe can be shortened by short loops or catch loops. Combinations of these measures are also possible.

A yarn of approximately 200-250 denier which yarn may also have a high rate of shrinkage, is usually used as the closing thread S. If the actual stocking is knitted from a very strong thread, it is possible, in a modification of the method according to the invention, to use the thread serving to form the stocking also as a toe-closing thread. In this case the thread in one row is picked out of the mesh and drawn out in the manner

described. A hook-shaped member which penetrates the cover disk 50 can be used to extract the thread.

To reduce the amount of material accumulated on the closed toe, it is naturally also possible to produce 5 loosely knitted loops or to use a thinner yarn in the toe-closing zone.

The invention is not limited to the embodiment shown in FIGS. 1 to 13. A closing thread can be resiliently retained by means other than suction, for example, by a resilient clip. The removal of the toe-closing thread does not need to be effected by a hook. A pivot lever or a cam-shaped plate could be used to solve this problem. The thread must not be secured against withdrawal by knotting. It would also be conceivable to 10 weld, glue or sew the thread ends together. It is by no means necessary for the closing thread to be knitted into a two-layered loop. With simple stockings it may be sufficient to lay the closing thread into only a single layer of mesh.

20 The circular knitting machine, which is shown in FIG. 14 to be suitable for carrying out a modified method according to the invention, is basically the same in construction as the machine shown in FIG. 7. Corresponding parts are provided with the same reference numerals as in FIG. 7 so that a new description is 25 unnecessary.

In the machine according to FIG. 14 in place of the welt dial there is a stationary cover disk 141 mounted on the yoke 20 in the vicinity of and co-axial with the upper edge of the needle cylinder. The disk has in its centre an opening 122 which tapers conically upwards. A hook 123, which is guided for longitudinal displacement through a bush 124 in the yoke 20, can be moved up and down through this opening 122. In the vicinity 30 of the upper edge of the opening 122 there is arranged a welding apparatus comprising a fixed welding jaw 125a and a displaceable welding jaw 125b. To drive the latter toward the fixed jaw a rotatable cam 126 is mounted on the cover disk 141. One or both jaws can 35 be heated. The cam 126 can be rotated by a suitable control device 129, the cam being drivingly connected to the control device by any conventional intermediate linkage, as schematically illustrated by the dash-dot line in FIG. 15.

40 In addition two thread guides 127a and 127b are mounted in a staggered relationship to one another on the yoke 20. A thread F or S can be fed to these guides from bobbins, which are mounted above the yoke 20 and schematically represented at 128a and 128b. In FIG. 14 both thread guides 127a and 127b are in an operative position so that they each feed a thread to the 45 needles 5. However, the thread guides can also be pivoted upwards from which position they do not feed thread to the needles.

50 The cams 11, 12, the thread guide 127a and 127b the cam 126, the hook 123 and the welding device 125a,b are actuated by a control apparatus which is schematically represented at 129 and can be, for example, a cam drum driven by the main drive 2 of the machine. The cam drum can be connected to the parts to be controlled by plungers or control pistons, for example.

55 During the operation the needles 5 combine with the sinkers 17 to form a mesh G from the thread F. This is a conventional operation and does not need to be described in detail.

60 To produce a stocking with a closed toe, the machine shown in FIG. 14 is operated as follows:

If the marginal section forming the toe is produced during the knitting operation, the thread guide 127b is lowered into the working position. It therefore feeds to the needles the additional closing thread S which is somewhat stronger than the thread F.

First, the toe-closing thread S is fed to all the needles 5. As is schematically illustrated in FIG. 15, a section in which the closing thread S is held in every loop of the mesh is thereby produced between two peripheral points a. A needle selection is then made in the usual manner. The toe-closing thread S is only laid into some of the needles 5 from the peripheral point a over the entire periphery of the mesh G and then as far as the peripheral point b. At the point b the thread guide 127b is moved into the inoperative position so that the needles no longer grip the closing thread S, thereby producing a floating section S_f of the closing thread which extends transversely through the interior of the mesh G. At the point c the thread S is fed again to the needles, the needle selection being made in such a manner that the thread is only gripped by a few needles. Then this operation is again continued around the periphery of the mesh G as far as the point d, where the needle selection is cancelled and the thread S is again fed to all the needles, thereby forming a closing section d—d 25 in which the closing thread S is again held in all the loops. Then the thread S is laid out, with the thread then being cut off and retained whatever manner desired, such as manually or automatically in the usual manner.

The control of the needles is briefly described below with the aid of FIG. 16, which is a schematic representation showing a development of stationary cam portions mounted on a cylindrical periphery disposed for engaging the projecting needle feet for controlling the needles 5 rotating in the direction of the arrow P. A first cam portion 130 guides the needles 5 upwards so that they grip the thread F which is fed through the thread guide 127a lowered into an operative position. The cam portion 131 draws off the needles until the loops of the mesh are formed from the thread F on the opposite cam portion 132. After the thread S is initially knitted into all the loops of the mesh G, the cam portion 133 picks out those needles which are intended to grip the closing thread S in the peripheral zone a—b or c—d. The cam portion 134 draws off the selected needles so that, with the cam portion 135, the closing thread S is held by the needles 5 and the sinkers 17. The cam portion 136 pushes needles 5 upwards so that the loops formed by the cam portions 131 and 132 for controlling the needles 5 are brought into a position under the latches of the needles and, with the cam portions 134 and 135, new loops can be formed by these needles with the closing thread S.

The needle selection can be effected in various ways depending on the number of needles used in the cylinder 3. FIG. 17 shows, for example, needles inserted in the cylinder 3 for interlacing the closing thread S in a 1:1 selection in the zones a—b and c—d. FIG. 17 shows that two types of needles 5 are used with controlling feet of differing length so that, if required, every second needle can be moved upwards into a thread receiving position such as the cam portion 133 by means of an associated cam portion. In the example according to FIG. 18 a needle selection is possible both in the ratio of 1:1 and in the ratio of 1:3. In this case three different types of needles are used so that, if necessary, every

second or fourth needle can be raised into a thread receiving position.

In FIG. 19 can be seen the mesh which is formed in the zone b—c or c—d by a 1:1 selection of needles 5. The 5 closing thread S is interlaced into every second loop M of the mesh G and floats over the intermediate loop.

FIG. 20 shows the corresponding loop configuration with a 1:3 selection of needles. In this case the closing thread S is interlaced into every fourth loop M of the 10 mesh G formed from the thread F and floats over the three intermediate loops.

As soon as the toe-closing thread S is laid out, the 15 floating section S_f is gripped by the downward guided hook 123. The mesh G is cast off the needles 5 in the usual manner. The hook 123 is then guided upwards drawing the upper edge of the mesh into the conical opening 122. This opening is too narrow to allow the compressed mesh to pass through and the mesh is therefore retained therein. On the other hand, the closing thread S is drawn through the opening 122 by the hook 123 so that the view shown in FIG. 21 is produced. The thread S which is interlaced into the mesh G more than twice around its periphery is drawn out. The edge of the mesh is thereby narrowed down at this 20 point whereupon the opening O in the tubular mesh is constricted. The further the thread S is drawn out (cp. FIG. 22), the narrower the opening O becomes until finally the edge of the tubular mesh is fully constricted and a closed toe S_p is formed, as shown in FIG. 23.

30 Then the toe-closing thread S only needs to be secured to prevent withdrawal. This is effected in the illustrated embodiment by moving the heat welding jaws 125a and 125b together so that the thread S is welded to the constricted edge of the mesh. If both the thread F and the thread S consist of thermoplastic material, then a completely sealed and welded closure is produced at this point. However, it is even sufficient if only the thread S is made of thermoplastic material and welded by means of welding apparatus to the edge of 35 the mesh.

In the last described embodiment only one floating section S_f is formed. However, to increase security against tearing, the closing thread S can also form a plurality of floating sections, as schematically represented in FIG. 24. The closing thread S is again knitted into every loop of the mesh G in the initial peripheral section a—a, which is followed by a peripheral section a—b above which only some of the needles knit or interlace the closing thread S. This is followed by a first floating section S_{f1} above which the closing thread S is laid out. The thread S is again fed to a certain number of the needles 5 from point e as far as point f on the periphery. This is followed by a second floating section S_{f2} extending as far as the peripheral point g, where the 40 thread is again interlaced by part of the needles as far as peripheral point h. Next there is a third floating section S_{f3} extending as far as the peripheral point i. Then the thread S is again fed to some of the needles over a section of the periphery as far as point k. This is followed by another floating section S_{f4}. The floating sections S_{f1} and S_{f3} overlap one another and lie parallel to one another just as the sections S_{f2} and S_{f4}. The thread S is interlaced between the peripheral points l and m as

45 well as n and o by some of the needles, while intermediate floating sections S_{f5} and S_{f6} are formed. This is followed by sections with partially interlaced thread S between the points p and q as well as r and s, another 50

floating section S_{77} being formed between q and r and a final floating section S_{78} following point s . The latter ends at the point c which is connected to a section having partially interlaced thread extending as far as the peripheral point d . This is then followed by the normal closing section $d-d$ above which the thread S is again knitted into all the needles. Therefore, a total of eight floating sections are produced two of which run parallel to one another. The floating sections are covered by at least two sections in which the thread S is interlaced into part of the needles as shown by the loop configurations in FIGS. 19 and 20. At least some of the floating sections are positioned above and extend over the hook 123 as possessed by the embodiment shown in FIG. 14 so that when hook 123 is pulled upwardly, the hook 123 or a similar tool grips the floating sections and draws them through the conical opening 122. Obviously, sufficient numbers of the floating sections are gripped by the hook and withdrawn so as to enable tensioning of the interlaced thread through 360° to permit proper closure of the stocking toe. With this embodiment the risk of breaking the closing thread during removal is totally eliminated. Moreover, the width of the knitted section which is constricted upon the closure of the toe is even greater.

The invention is not restricted to the embodiments shown in FIGS. 14 to 23. The number of completely freely floating sections can be selected, depending on the circumstances; it is also possible to determine into how many needles the closing thread is interlaced in the intermediate sections. The toe does not need to be constricted and secured by the means described. Instead, the stocking may be closed by a separate device outside the circular knitting machine. Instead of welding the toe and/or the closing thread together, gluing, sewing or knotting are also possible. A combination of these measures is also conceivable. The use of an ultrasonic welding apparatus might be particularly advantageous for securing the closing thread. It is not absolutely necessary for the mesh to be retained and the closing thread drawn out. The reverse process is also possible. For example, it is possible to use a fixed hook into which the closing thread is drawn. The toe itself is then closed when the stocking is drawn downwards through the funnel 14. There must be other components present inside the funnel to release the closing thread from the hook and to secure it against withdrawal.

The method according to the invention does not always have to be carried out by a machine having no welt dial as shown in FIG. 14. In fact, a completely conventional circular knitting machine equipped with a welt dial can be used, in which case the hook would then have to pass through the centre of the rotating welt dial. In this case the welding apparatus 125a, b or a corresponding unit for securing the closing thread S would have to be supported under the rotating welt dial.

Sometimes it is not absolutely necessary to interlace or knit in a single closing thread. If the stocking toe is knitted with sufficiently strong thread, it may also be used for the actual closing thread and removed in the vicinity of a course in order to constrict and close the toe.

To prevent a surplus of material accumulating in the centre of the toe, the number of needles can be reduced in the known manner in the vicinity of the toe.

A thinner thread may also be used in this part of the stocking. Additional thread guides would then have to be provided parallel to the thread guide 127a.

In order that the closure is produced in the hollow recess under the toes when the stocking is worn, the upper part of the toe can be produced by an oscillating action. When the stocking consists simply of a tube, the loops in the upper part of the toe can be more loosely knitted than those in the lower part. Also, in the latter case, catch loops which shorten the mesh can be formed in the lower part of the toe. Through one of these measures or a combination thereof, the mesh becomes longer in the upper part than in the lower part of toe. The closure is therefore brought further and further under the toes, depending on the difference in length, whenever the stocking is worn.

According to the method of the invention it is also obvious that stocking toes can be produced from a two-layered mesh. In this connection there will not be such an accumulation of material as in the known method of twisting the toe is only knitted with a reduced number of needles and not twisted. Also the length of the two-layered toe may be freely determined irrespective of the diameters of the cylinder and welt dial. For example, part of the toe can be knitted in a single layer, and the end portion in a double layer. In this case the material accumulating in the centre of the toe is still less than in the completely one-layered toe, because the closing rows are not concentrated exactly in the centre of the toe. In this connection the closing thread is knitted in the centre of the two-layered mesh according to the same principle and also drawn out again to close the toe.

As can be seen in FIG. 25 which shows a modification of the method according to FIGS. 15 and 16, a toe-closing thread S is again knitted or interlaced into a tubular mesh G in the vicinity of its edge leading to the toe. The thread S is shown by broken lines in the drawing.

In this method the closing thread S is first fed to the needles over part of the periphery of the mesh. It is thereby knitted over this peripheral section into the mesh. After the circular knitting machine turns by a certain distance, a quarter-turn in the embodiment according to FIG. 25, the thread S is again laid out. The point at which the thread is first laid out is designated by a^1 in FIG. 25. The closing thread is then laid out for a full turn of the machine, thereby forming a loop Sch_1 the length of which is equal to the radius of the mesh G . In the centre of the mesh there is arranged an extracting member A , which can be, for example, the hook 123 of the machine shown in FIG. 14 projecting through the centre and into the upper edge of the needle cylinder. In this case the loop Sch_1 is laid around the shaft of the hook 123. The closing thread is then laid in again at point b^1 in order to be laid out again at c^1 following another quarter-turn. The thread is again laid out for a full turn of the machine thereby forming a loop Sch_2 which also encircles the extracting member A . The thread is laid in again at d^1 . The same process is repeated at points e^1 , f^1 and g^1 , h , whereupon other loops Sch_3 and Sch_4 are formed. All the loops are suspended from the extracting member A . After the mesh G is cast off the knitting needles the loops Sch_{1-4} are extracted co-axially to the retained tubular mesh so that the mesh is closed in the manner described with reference to FIGS. 21 to 23. Finally, the loops are se-

cured against withdrawal and for this purpose they can, for example, be knotted, glued or sewn together or welded by ultrasonic means or the application of heat.

There are also cases where it is sufficient for a single loop to be formed by the closing thread. It is also possible to use two, three, five or more loops. The only essential requirement is that the closing thread should pass at least once around the entire mesh so that the latter is constricted on all sides. The number of loops is determined by how great the resistance is to the removal of the closing thread. If the closing thread is particularly exposed to the risk of tearing or breaking, it is expedient to form two or more loops at the same point on the periphery so that the pulling force during extraction is distributed over several loops at the relevant point. This last alternative is indicated with broken lines in the drawing by a loop Sch¹.

Various methods of closing the toe of stockings have hitherto been described. For this purpose a closing thread is knitted into the edge of the mesh connected to the toe and passes at least once around the periphery of the mesh. It is either laid in so that it forms at least one floating section or so that, after the two ends are laid out, they can project from the mesh and be held. Then, by removing the floating section while a loop is formed or by extracting the two projecting ends while the mesh is constricted, the thread is drawn out so far that the toe is closed. If the knitting thread itself is strong enough in the vicinity of the toe, it is possible to dispense with knitting a special closing thread and drawing out a thread of the mesh so far that the toe is constricted. In any case a closed toe S_p is formed, as shown in FIG. 31a. Two closing thread ends S_e or S_a project from this toe, if the closing thread has been drawn out by its ends. If a floating section is drawn out, a loop Sch is formed as shown by the broken line in FIG. 31a.

Another embodiment of the invention, described below, concerns the problem of how the closing thread S can be secured against withdrawal after it is drawn out. The two thread ends or the loop are twisted in the manner shown in FIG. 31b so that a twisted piece of thread is formed. This operation gives rise to a longitudinal tension in the twisted piece of thread. If the twisted thread is then loosened, it rolls together in the manner shown in FIG. 31c and forms a ball K. Only the first stage of the formation of the ball is shown in FIG. 31c. In actual fact the twisted thread rolls up to form an even thicker ball. Adhesive is then applied, for example by spraying, to this ball, as is shown in FIG. 31c by an arrow Pf. Before twisting, the adhesive can be additionally or even solely applied to the thread ends. This merely depends on closely joining the two twisted threads and the sections forming the ball so that they cannot be loosened. The toe-closing thread S is then effectively prevented from withdrawing into the mesh.

The method just described can be put into practice on a circular knitting machine as shown in FIGS. 26 to 30.

Where the components of the machine shown in FIGS. 26-30 correspond to those of the machines shown in FIGS. 7 and 14, they have the same reference numerals and require no further explanation.

A couple of thread guides 227a, 227b, are again mounted on the yoke 20 in a manner not shown in de-

tail, each thread guide feeding a thread to the needles 5 from unshown bobbins rotatably mounted on the frame of the machine.

A conventional welt dial 231 containing transfer sinkers 233 in radial grooves 232 is mounted concentrically with the needle cylinder 3 and slightly above its upper edge. The welt dial 231 is carried by a fixed stationary bridge 234 and driven synchronously with the needle cylinder 3 by the main shaft 6 via a toothed gear 235 and a bush 236 rigidly supported in the welt dial 231. The movement of the transfer sinkers 233 is controlled by a ribbed cam 237 which is mounted in a fixed cover disk 238. The transfer sinkers 233 serve to form the double welt in stockings; they temporarily take over one or several courses of loops from the needles 5 to which the courses are returned after the double welt is formed. As can be seen particularly in the enlarged sections in FIGS. 27 to 30, the welt dial 231 has a central opening 239 which tapers downwards. A hook 240 forming a co-axial extension to a shaft 241 of an electromotor 242 passes through the opening 239. The shaft 241 and the hook 240 which is an extension of the former extend co-axially with and through the interior of the bush 236. The motor 242 obtains its current from a feed circuit 243 comprising a cam switch 243a and a source of current 245. The motor 242 is articulately mounted on the end of one arm 244a of a lever 244 pivotably mounted at 245a in the yoke 20. The other arm 244b of the pivot lever 244 forms a tracking projection which is engaged on a cam control drum 246 by the action of a tension spring 247. The cam control drum 246 is likewise mounted in the yoke 20 and driven by the drive 2, as indicated by broken lines at 248. An adhesive spray nozzle 250 is rigidly mounted in a hollow chamber 249 which is bounded at the bottom by the base of a recess in the welt dial 231 and on the side by the lower edge of the bush 236. A textile adhesive can be fed from a container 251 through a pipe 252 to the adhesive spray nozzle 250. The container 251 has a pump which can be driven by means of a plunger 253. A pivot lever 254 bears against the plunger, said lever being pivotably mounted at 255 in the yoke 20 and engaging with a tracking projection 254a on a cam plate of the cam control drum 246.

A small plate 256 is stationarily positioned within the rotating sleeve 236 above the chamber 249 and has a central opening 257 through which the hook 240 passes. The part of the feed pipe 252 which extends immediately above the adhesive spray nozzle 250 is fixed to the plate 256 and extends through another lateral opening. A movable cutting edge 258 bears against the lower side of the small plate 256, a fixed cutting edge of the cutters being formed by the lower edge of the recess 257 in the small plate 256. The movable cutting edge 258 is supported by the lower end of a rotatable shaft 259 which penetrates another lateral opening in the small plate 256.

The drive of the cutters 256-258 is shown in FIGS. 29 and 30. The upper end of the shaft 259 is provided with an arm 259a laterally deflected at right angles. This arm 259a bears against a swinging arm 260 which can rotate about an axle 261 supported on the cover disk 238. A guide 262 is non-rotatably joined to the arm 260 and is connected to a two-armed pivot lever 264 by another guide 263. This lever in turn can be pivoted about a vertical axle 265 supported in part of the cover disk 238. A lever 266 mounted in the yoke 20

bears against the side of the lever 264 lying opposite the axle 265 in relation to the guide 263, a tracking projection 266a of said lever 266 engaging on a cam plate of the cam control drum 246.

The mouth of a suction tube 267 is mounted above the upper end of the bush 236 and connected to an unshown source of suction.

The described circular knitting machine of FIGS. 26 to 30 operates as follows:-

In a rotating needle cylinder 3 the needles 5 co-operate with the cast-off sinkers 17 in the usual manner to form a mesh. In this connection the thread is fed from the thread guide 227a to the needles. To form the double welt the first courses are temporarily transferred to the sinkers 233 of the welt dial 231. These operations are conventional and do not need to be described in detail.

When the knitting operation reaches the edge zone of the stocking connected to the toe, some of the needles are drawn out of the knitting zone and a two-layered loop is formed by the remaining needles. Approximately in the centre of this knitted loop an additional closing thread S is fed through the thread guide 227b to all or some of the needles so that it passes at least once around the entire periphery of the mesh. The closing thread is then temporarily laid out. At this time one end of the closing thread is held in the mesh whereas the other end extends through the thread guide 227b to the thread package. The needle cylinder continues to rotate whereas the thread guide, of course, is stationary. The hook 240 at this time is in its lowered position. The needle cylinder pulls the forward end of the closing thread which is being held in the mesh along on its circular path. Since the rearward end of the closing thread is held in the stationary thread guide, the floating portion of the closing thread is being wound around the shaft of the lowered hook 240. After one or more revolutions of the needle cylinder there are one or more windings of closing thread around the shaft of the hook so that the hook in its upward movement engages the closing thread irrespective of the momentary relative position between the hook and the needle cylinder. The closing thread is then again fed to some or all of the needles so that it passes at least once around the periphery of the mesh. Finally the closing thread is laid out again by pivoting the thread guide 227b upwards and cut off by an unshown cutting device on the cover disk 238. Then the second half of the two-layered loop is knitted, and all the needles are brought into the working position. At completion of this two-layered loop, the floating section is engaged with the hook 240. The cam drum 246 then actuates the motor 242 so that the latter can pivot upwards by means of the spring 247. The hook 240 then extracts a portion of the closing thread causing the two-layered closing zone to be constricted. After the closing rows are knitted the mesh is cast off the needles. The motor 242 is pivoted further upwards by the force of the spring and the closing thread is almost completely drawn out of the mesh causing construction of the toe due to the toe S, being drawn into the downward tapering opening 239 of the welt dial 231. The mesh is retained in this opening while the hook 240, moving upwards through the opening 239, extracts the closing thread resulting in the formation of a loop Sch. The edge of the mesh leading to the toe is thereby constricted and a closed toe is formed.

During the removal of the closing thread the motor 242 is set into operation by the cam switch 243a so that both the shaft 241 and the hook 240 rotate. The sections of the closing thread forming the loop Sch are thereby twisted together in the manner shown in FIG. 31b. At this stage adhesive can be applied by the spray nozzle 250 to the twisting sections of the closing thread by actuating the pump 253 in the adhesive supply container 251. After the twisting is completed, the hook 240 is again guided slightly downwards so that the ball K shown in FIG. 31c is formed in the chamber 249 due to the loosening of the twisted thread. Finally a textile adhesive is sprayed from the spray nozzle 250 on to the ball K so that the ball or the twisted closing thread is firmly glued. The hook 240 is then drawn at least into the opening of plate 256 by moving the motor 242 upwards.

At this point the cam control drum 246 pivots above the parts 266, 264, 263, 262, 260 and 259, and the movable cutting edge 258. In co-operation with the cutting edge, fixed opposite and formed by the lower edge of the opening 256, the movable cutting edge 258 cuts off the portion of the twisted closing thread above the ball K. This portion is drawn upwards with the hook and sucked through off the hook into the suction tube 267. As a result of the closing thread being cut off, the stocking together with the closed toe and the closing thread secured against withdrawal falls downwards into the needle cylinder 3 from where it is transported in the usual manner.

If, instead of the simple cast-off sinkers 17, special sinkers as shown in German Pat. No. 1,169,072 and 1,201,939 are used with an additional groove so as to be capable of assuming the function of the transfer sinkers 33, then the needle cylinder is freely accessible from above on account of the welt dial being omitted so that it can be provided with an arrangement as shown in FIGS. 7 to 13. The closing thread is drawn out by this device while two projecting thread ends are gripped. These thread ends can in turn be extracted, twisted and glued together by means of a rotating and longitudinally movable tool. No floating section needs to be formed in this case.

In place of a spray nozzle other adhesive applicators, such as rollers, may be used between which the twisted thread is drawn.

The motor 242 does not need to be pivoted upwards; it can be mounted in a longitudinal guide, co-axial with the needle cylinder, and longitudinally displaced therein.

No separate motor need be used to drive the hook 240; the hook can also be rotated and longitudinally displaced by the main drive of the machine via corresponding cam or lever mechanisms.

If the mesh is formed from a sufficiently strong thread, a separate thread for closing the toe can be omitted. A thread guide is also thereby rendered superfluous. The hook 240 then grips a floating section of the thread forming the mesh and draws it out in the manner described.

What we claim is:

1. A method for closing the toe of a stocking-like article produced in the form of a tubular mesh on the needles of a circular knitting machine, comprising the steps of interlacing an additional toe-closing thread into the tubular mesh in the vicinity of its edge connected to the toe so that the closing thread passes at

least once around the periphery of the mesh, pressing the mesh off the needles, providing a frame element having a small opening therethrough in the circular knitting machine, gripping the closing thread and pulling a part of the closing thread through said opening whereby the mesh is pulled partially into said opening with the opening being too small to permit the mesh to pass therethrough so as to restrain further movement of the mesh, then pulling further on the closing thread to partially withdraw a portion of the closing thread from the mesh for constricting same until an essentially closed toe is formed, and then securing the withdrawn portion of the closing thread for preventing the withdrawn portion of the closing thread from being pulled back into the mesh.

2. A method according to claim 1, including the steps of interlacing the closing thread into and out of the mesh so that, after being laid out of the mesh, the closing thread forms two sections projecting from the mesh, and gripping the projecting sections to permit withdrawal of the closing thread so as to constrict the mesh.

3. A method according to claim 2, wherein the two projecting sections of the closing thread are rigidly clamped at a point spaced from the mesh, and the projecting sections are gripped at a point between the clamping point and the mesh and then drawn out of the mesh while the mesh is retained in the small opening of the frame element.

4. A method according to claim 1, including the step of interlacing the closing thread into and out of the mesh so that it forms two projecting sections which project from the mesh and an intermediate floating section which is also free of the mesh, and gripping said intermediate section for partially withdrawing the closing thread so as to constrict the mesh.

5. A method according to claim 2, wherein the two projecting sections project out of the mesh at substantially the same point on the periphery thereof so that the two projecting sections are in juxtaposition.

6. A method according to claim 1, wherein the closing thread is secured against being pulled back into the mesh by knotting the withdrawn portion of the closing thread.

7. A method according to claim 1, wherein a two-layer closing zone is formed in the mesh, and the closing thread is interlaced approximately in the center of the closing zone.

8. A method according to claim 1, wherein the closing thread comprises a yarn of approximately 200 to 250 denier and having a high rate of shrinkage.

9. A method according to claim 1, including the step of interlacing an intermediate section of the closing thread into the mesh and knitting opposite end sections of the closing thread into the mesh for holding the closing thread therein, the intermediate section of the closing thread being interlaced into the mesh so that the closing thread has at least one floating section which is disposed intermediate its end sections and is free of the mesh, said floating section comprising said part of the closing thread which is pulled through said opening, and gripping the floating section of the closing thread and applying a withdrawal force thereto to cause constriction of the mesh by drawing the mesh into the small opening.

10. A method according to claim 9, wherein the closing thread is stronger than the thread used in the mesh.

11. A method according to claim 9, wherein said gripping the closing thread involves gripping the floating section of the closing thread and pulling it through the opening whereby the mesh is pulled partially into the opening, and wherein said pulling further on the closing thread involves pulling on the floating section of the closing thread to partially withdraw said portion of the closing thread from the mesh for constricting the mesh.

12. A method according to claim 9 wherein said interlacing intermediate floating section is formed as a loop and has a length at least substantially equal to the radius of the tubular mesh.

13. A method according to claim 12, including the step of providing an extracting member in the center of the mesh for permitting the floating section to be looped therearound.

14. A method according to claim 12, wherein the closing thread is interlaced into the mesh so as to form a plurality of circumferentially spaced, loop-like floating sections extending radially inwardly from the mesh.

15. A method according to claim 12, wherein the closing thread is interlaced into the mesh so as to form at least two loop-like floating sections extending radially inwardly from the mesh from substantially the same point at the periphery thereof.

16. A method according to claim 1, wherein said securing the withdrawn portion of the closing thread includes the steps of twisting the withdrawn portion of the closing thread and gluing the twisted portion together to prevent same from being drawn back into the mesh.

17. A method according to claim 16, including the step of permitting the twisted withdrawn portion of the closing thread to slacken so as to form into a ball.

18. A method according to claim 16, wherein said gluing of the twisted portion includes applying an adhesive to the withdrawn portion of the closing thread prior to twisting thereof.

19. A circular knitting machine for producing a tubular mesh and for closing the end of the mesh so as to form the toe of a stocking, said machine comprising:

knitting means for producing a tubular knitted fabric or mesh, said knitting machine including a rotatable needle cylinder having a plurality of longitudinally displaceable needles mounted thereon; said knitting means further including a sinker supporting ring surrounding the upper end of the needle cylinder and having a plurality of radially movable sinkers disposed therein; first guide means for feeding thread to said needles for permitting formation of said tubular mesh; means for causing a closing thread to be interlaced into the tubular mesh in the vicinity of one edge thereof with said closing thread passing at least once around the periphery of the mesh, said means including a second guide means for feeding the closing thread to said needles; a cover disk stationarily mounted coaxial with and above the upper edge of the needle cylinder, and the cover disk having a central opening therethrough which is too narrow for the mesh to pass therethrough;

constriction means (1) for engaging the closing thread after it has been interlaced into and around said tubular mesh for pulling said mesh, after it has been cast off said needles into the central opening of said cover disk and (2) for withdrawing at least a portion of said closing thread from said mesh when said mesh is restrained by said opening so as to cause a constriction of said mesh, whereby one end of said tubular mesh is substantially closed; and

securing means for securing said closing thread relative to said mesh for preventing the withdrawn portion of said closing thread from being pulled back into said mesh to thereby maintain the one end of said mesh closed.

20. A knitting machine according to claim 19, wherein the cover disk has a slot extending from the edge of the disk inwardly toward and in communication with the opening, clamping means including a movable clamping member disposed adjacent the cover disk for temporarily gripping the closing thread, the constriction means including a pulling device mounted between the clamping member and the opening for withdrawing the closing thread, and the securing means being mounted adjacent the opening in the cover disk for preventing the closing thread from being pulled back into the mesh.

21. A knitting machine according to claim 20, wherein said clamping means includes a resilient deflecting pin associated with the clamping member and located between the clamping member and the second guide means, the clamping member being movable between an open position wherein it is spaced from the disk and a closed position wherein it is in engagement with the disk, and the free end of the deflecting pin extending beyond the end of the clamping member whereby said pin is disposed in engagement with said disk when said clamping member is spaced at a location intermediate its open and closed positions.

22. A knitting machine according to claim 20, wherein the pulling device includes a vertically displaceable extracting hook disposed for engagement with the closing thread.

23. A knitting machine according to claim 22, wherein said cover disk is provided with a recess therein, and said extracting hook has a head portion disposed for reception in said recess when the extracting hook is in its lowermost position.

24. A knitting machine according to claim 20, wherein said securing means includes a knotting device mounted above the opening in said cover disk for engaging the withdrawn portion of the closing thread and for forming a knot therein, and a vertically movable thread control plate disposed adjacent said knotting device and positioned for engagement with the withdrawn portion of the closing thread for permitting said knotting device to coact with said withdrawn portion of said closing thread so as to form a knot therein.

25. A knitting machine according to claim 24, including cutter means associated with said knotting device for cutting said closing thread.

26. A knitting machine according to claim 24, wherein a cutting device is located adjacent the cover disk for cutting the closing thread, said cutting device including a cutting edge formed on the lower edge of the thread control plate, and a second cutting edge rig-

idly mounted on the cover disk opposite from the thread control plate.

27. A knitting machine according to claim 20, wherein the slot formed in said cover disk extends through said disk and extends from said opening toward the edge of said disk approximately in the form of a steep logarithmic spiral.

28. A knitting machine according to claim 20, wherein the opening formed in said cover disk is of a conical configuration.

29. A knitting machine according to claim 20, further including means interconnected to said securing means, said constriction means and said clamping means for synchronizing and controlling the operations thereof.

30. A knitting machine according to claim 19, wherein said means for interlacing said closing thread into said mesh causes a central portion of said closing thread to be interlaced with said mesh with the two end portions of said closing thread projecting from the mesh.

31. A knitting machine according to claim 19, wherein the means for causing a closing thread to be interlaced into the mesh causes the closing thread to be held in the mesh by knitting end portions of the closing thread into the mesh, an intermediate portion of the closing thread being free of connection to and floating relative to the mesh, and said constriction means including a movable hook disposed for engagement with the floating section of said closing thread.

32. A knitting machine according to claim 31, and wherein said hook is movable through said opening for engaging the floating section of said closing thread and for drawing said floating section through said opening.

33. A knitting machine according to claim 32, wherein said securing means comprises a gluing device disposed adjacent said opening for securing the withdrawn portion of said closing thread.

34. A knitting machine according to claim 32, wherein said opening converges conically in a direction away from the mesh whereby the mesh will partially enter said opening and is constrained from passing therethrough.

35. A knitting machine according to claim 31, further including means movably mounting said hook for both rotatable and vertical movement, said hook being rotated after same has engaged and partially withdrawn said closing thread from said mesh for causing twisting of the withdrawn portion of said closing thread, and applicator means disposed adjacent said hook for applying an adhesive to the twisted portion of said closing thread.

36. A knitting machine according to claim 35, wherein the means mounting the hook includes a motor having a shaft on which the hook is secured, and means pivotably mounting said motor for enabling vertical displacement of said motor above the needle cylinders substantially in the longitudinal direction of the shaft.

37. A knitting machine according to claim 35, wherein said applicator means includes a spray nozzle disposed adjacent the path of movement of the hook for spraying an adhesive onto the twisted portion of the closing thread.

38. A knitting machine according to claim 37, further including cutting means for cutting the withdrawn por-

tion of the closing thread after the adhesive has been applied thereto.

39. A knitting machine according to claim 38, further including cam means for synchronously controlling the movement of the hook, the applicator means and the cutting means.

40. A knitting machine according to claim 39, wherein the means mounting the hook include an elongated lever having a portion thereof coacting with said cam means and also having a motor pivotally mounted thereon at a location spaced from said cam means, said motor having a shaft with said hook fixedly secured to said shaft, whereby said motor when energized causes rotation of said hook, with pivotable movement of said lever by said cam means causing said motor to be substantially vertically displaced in a direction substan-

tially parallel to the longitudinal direction of said hook.

41. A knitting machine according to claim 20, further including a cutting device located adjacent the cover disk for cutting the closing thread.

42. A knitting machine according to claim 32, wherein said securing means comprises a welding device disposed adjacent said opening for securing the withdrawn portion of said closing thread.

43. A knitting machine according to claim 41, further including suction tube means associated with the clamping means for drawing off severed thread ends produced by said cutting device and for temporarily retaining an end of the closing thread.
